UNITED STATES PATENT OFFICE

2,613,706

WEIGHTED FEED ROLL FOR WOOD-
WORKING MACHINES

Orson P. Smith, Seattle, Wash., assignor, by
mesne assignments, to Smithway Machine Co.,
Inc., Seattle, Wash., a corporation of Wash-
ington

Application March 26, 1949, Serial No. 83,600

5 Claims. (Cl. 144—248)

1

This invention relates to woodworking machines and it has reference more particularly to improvements in machines that are designed especially for the manufacture of moldings and the like from strips of wood, for example, strips made from mill waste or from waste rippings.

It is the principal object of the present invention to provide a novel, desirable and satisfactory feeding mechanism for woodworking machines of the above kind whereby strips of stock material may be fed, end to end and at a constant and high lineal speed, to the cutter heads for the making of moldings from the strips.

It is also an object of the invention to provide a strip feed mechanism as above stated, comprising dual, synchronously driven rollers that are weighted to maintain frictional driving contact with the stock to advance it to the cutter head and which rollers are so supported that the likelihood of damage to strips, by reason of the feed rolls dropping between successive strips, will be eliminated.

It is also an object of the invention to provide a strip feed mechanism embodying feed rolls arranged in tandem and having a novel form of pressure exerting means, common to both rolls but providing that one fed roll cannot drop to any substantial extent below the level of the other.

Still further objects of the invention reside in the details of construction and combination of parts and in their mode of operation as will hereinafter be fully described.

In accomplishing the above mentioned and other objects of the invention, I have provided the improved details of construction, the preferred forms of which are illustrated in the accompanying drawings, wherein:

Fig. 1 is a perspective view of a woodworking machine embodying the improvements of the present invention therein.

Fig. 2 is an elevation of a portion of the machine, showing the feed rolls and pressure mechanism embodied by the present invention.

Fig. 3 is a top, or plan view of the feed rolls as shown in Fig. 2, and their driving means.

Fig. 4 is a view illustrating the arrangement of chain belts whereby the feed rolls are driven in unison.

Fig. 5 is a vertical section taken on line 5—5 in Fig. 3.

Fig. 6 is a vertical section taken on line 6—6 in Fig. 3.

Referring more in detail to the drawings:

In Fig. 1, I have illustrated a woodworking

2

machine in which a strip feeding mechanism embodied by the present invention has been incorporated. The machine, as therein shown, comprises a box-like base 10 on which a frame structure, designated in general by reference character 12, is secured. Associated with the machine in suitable manner is an electric motor 15 for driving the horizontal, upper and lower cutter heads, which in Fig. 1 are designated, respectively, by numerals 16 and 17. Also, there is an electric motor 18 mounted in the frame in suitable manner for driving a front, vertical cutter head designated by numeral 19, and a similar rear cutter head not shown. Strips of wood to be cut into moldings of definite pattern by means of the above mentioned cutter heads are advanced by a feed mechanism, presently to be explained, across a horizontal feed table 20 as guided by a vertical guide flange 21 extending upwardly from the back or inner edge of the table, as noted best in Figs. 2 and 3. The feed mechanism which characterizes this invention is located at the right-hand end of the machine, as seen in Fig. 1, and its construction and mode of operation will now be described.

Mounted within suitable openings provided therefor in the feed table 20, are freely revoluble rolls 22 and 23. These are revoluble on spindles 24 and 25, set in parallel relationship and at such position in the frame structure as to support the rolls flush with the table surface for the feeding of the strips thereacross. These rolls extend at right angles to the plane of flange 21 and path of travel of the strips to the cutter heads. Located substantially directly above the rolls 22 and 23 are driven pressure rolls 27 and 28, revolubly mounted by supporting axles 27' and 28' that extend from their inner ends. These axles are revolubly contained in bearings 29 and 30 which are equipped, respectively, with supporting arms 31 and 32 which are swingably mounted on a shaft 35 that is parallel with and located between the driven rolls and which extends rearwardly from a lug 40 that projects upwardly from the table 20 in alignment with the flange 21.

The means for and manner of mounting the two rolls 27 and 28 as above described provides that they may be moved directly toward or from the rolls 25 and 26, to adapt them to the feeding of pieces of varying thicknesses, and to bear directly against the top surface of a strip of wood to advance it along the table to the cutter heads.

55 It is herein provided that the driven rolls 27

and 28 shall maintain frictional driving contact with the wood strips but that they shall not be permitted, either singly or together, to drop to any appreciable extent toward the table surface as a strip passes from between them. It will be understood by reference to Fig. 2 that if such dropping of a roll should take place, the drop might damage a projecting tenon, or mar the forward end of the next incoming stick. The present invention provides that adequate feeding pressure on the stick shall be maintained by the feed rolls and that the rolls shall be permitted to rise should a stick of greater thickness enter between them and the lower rolls.

The means provided for maintaining downward pressure on and for limiting the extent of drop of the driven rolls comprises a vertical slide bar 36 that is mounted at its lower end for vertical movement in a guideway 37' formed in a bracket 37 that is bolted or otherwise fixed to the back face of the table 20, as is shown best in Fig. 6, the pressure bar 36 extending above and being disposed between the longitudinal axes of the driven pressure rolls 27 and 28. The bracket is formed with a rearwardly extended and upwardly directed arm 37x, spaced rearwardly from the table lug 40. The lug 40 and bracket arm are formed with bearings 38 and 39 in which the shaft 35, previously mentioned, is rotatably contained. The bar 36 is also formed with a vertical slot 36s through which the shaft 35 extends as a supplemental guide, as will be understood by reference to Fig. 5.

Extended horizontally from the bar 36, in opposite directions, at the same level, are arms 41-41', which respectively overlie the bearings 29 and 30. At their outer ends, these arms as shown in Fig. 5, extend through lugs 42-42' that extend upwardly from the bearings. It is shown best in Fig. 2 that the lugs are formed with passages, as at 43-43' to receive the arms 41-41' therethrough and that anti-friction rolls 44 are set in the lower surfaces of these passages for contact by the arms for the application of downward pressure. Likewise, cross rollers 45 are set in the top surfaces of these passages for the sustaining of the rolls against drop except to limited extent. It is to be observed that the vertical spacing of the rolls 44 and 45 is such that neither of the feed rolls will be permitted to drop when passing from the end of a stick to more than a very short distance. The slight or limited freedom of action provided for in this lost-motion connection permits the feed rolls to maintain adequate driving contact with the sticks yet prevents that damage which might result from an unrestricted drop of either roll.

The means for maintaining a downward force or pressure on the feed rolls to insure the desired frictional driving contact with the wooden strips comprises a weighted lever arm 50. This has a pivot pin connection 51 at one end, with the upper end of a standard 52 that extends upwardly from the table structure. The lever extends substantially horizontally and passes through a horizontal passage 53 in an enlarged upper end portion of the slide 36 as noted in Fig. 6. At its free end, the lever has a weight 55 slidably adjustable thereon, adapted to be secured at any set position of adjustment by a set screw 56 threaded therein to engage the lever. Rollers 57 are set in the passage 53 below and above the lever as noted in Figs. 5 and 6 to receive the pressure of the lever thereagainst.

In order to limit the downward extent of movement of slide 36 as required in setting it for the feeding of sticks of a definite thickness, I have equipped the slide 36 with an adjusting screw 60. This is threaded vertically through lugs 61-61' formed on the front side of the slide as seen in Fig. 2, and at its lower end the screw engages in direct supporting contact with the flat top surface of the previously mentioned lug 40. An adjusting wheel 65 is fixed to the upper end of the screw, and by turning it the feed screw may be so adjusted as to obtain a definite spacing of the feed rolls, as supported by the arms 41-41', from the table surface. The pressure of the feed rolls may be increased or decreased by moving the weight farther out or closer in on the lever arm.

To drive the feed rolls 27 and 28 in proper direction and in unison, their mounting axles are equipped at their inner ends with sprocket wheels 70-71, as seen in Fig. 3. These are aligned, respectively, with sprocket wheels 72 and 73 of like size on the inner end of shaft 35, and chain belts 75 and 76 are extended about the aligned sprocket wheels. Also, a sprocket wheel 77 is fixed on shaft 35 and a driving chain belt 78 is extended thereover. This latter belt may have any suitable driving connection with one of the electric motors. The direction of drive is such that sticks fed across the table beneath the driven rolls will be advanced toward the cutter head.

Assuming the machine to be so constructed, the mode of use would be as follows: First, the hand wheel 65 is manipulated to bring the feed rolls 27 and 28 to proper spacing from the table top, as determined by the thickness of material to be worked on. Then the weight 55 is adjusted along lever 50 to give the desired or proper frictional pressure of the rolls. Material is then fed into the machine, across the table top and is picked up by the feed rolls and advanced as indicated in Fig. 2, to the cutter heads, which would be equipped with cutters as required to produce moldings of any specified pattern.

The stock or strips may be fed end to end, and while the weighted lever 50, acting through the bar 36 and arms 41-41', maintains downward pressure on both feed rolls, neither roll is permitted to drop to any extent upon passing from the end of an advancing strip. Thus, damage to the stock is prevented without in any way making it difficult to advance the stock. In fact, the drop of a roll as it passes from the end of a strip is limited to such extent that the roll has no difficulty in picking up the next oncoming stick.

Feed mechanism of this kind is applicable to various kinds of machines other than that here shown and it is not the intent that the invention be restricted to any specific machine.

Having thus described my invention, what I claim as new therein and desire to secure by Letters Patent is:

1. In a woodworking machine, a table across which strips of material are adapted to be advanced endwise and in succession, driven feed rolls arranged in tandem and with which the entering strips successively engage for their advancement, mountings for said rolls supported for their independent movement toward and from the table, a vertically movable pressure bar associated with the table and extending above and disposed between the longitudinal axes of said rolls, means limiting the downward movement of the pressure bar in accordance

with the thickness of the strips being advanced across the table, means maintaining a downward force against the pressure bar, arms extending laterally in opposite directions from the pressure bar, each arm having a lost-motion connection with the mounting of one of the rolls and through which connection downward force may be transmitted from the pressure bar to the roll to press the roll into driving contact with a strip being advanced beneath the roll and whereby a limited downward movement of the roll relative to the pressure bar without transmission of downward force against the roll by the arm is permitted when said roll is not in contact with an advancing strip, said movement being definitely limited by the lost-motion connection of the roll mounting with the arm of the downwardly stopped pressure bar to that permitting easy pick-up of the next advanced strip by the roll.

2. In a woodworking machine, a table across which strips of material are adapted to be advanced, endwise and in success, driven feed rolls arranged in tandem, and with which the entering strips successively engage for their advancement, mountings for said rolls supported for their independent movement toward and from the table, a vertically movable pressure bar associated with the table extending above and disposed between the longitudinal axes of said rolls, means limiting the downward movement of the pressure bar in accordance with the thickness of the strips being advanced across the table, means maintaining a downward force against the pressure bar, arms extending laterally in opposite directions from the pressure bar, said mountings each being provided with a lug having a horizontal passage extending through the same, each of said arms extending through the passage in one of the lugs with clearance, whereby downward force may be transmitted from the pressure bar to the roll to press the roll into driving contact with a strip being advanced beneath it, and a limited downward movement of the roll relative to the pressure bar without transmission of downward force against the roll by the arm is permitted when the roll is not in contact with an advancing strip, said downward movement of the roll being definitely limited by the engagement of the arm with the lug to that permitting easy pick-up by the roll of the next strip advanced thereto.

3. A machine as recited in claim 2 wherein the said means maintaining downward force on the pressure bar comprises a lever arm pivoted at one end on the table to extend substantially horizontally and said pressure bar has a passage through which said lever freely extends in supporting contact with the bar, and a weight is adjustable along the lever arm to vary the bar pressure against the feed rolls.

4. A machine as in claim 2 including a revolvably driven shaft mounted parallel with and between the roll bearings, arms extended from

the said bearings and pivoted on said shaft, for the up-and-down movements of the feed rolls, supporting shafts for said rolls revoluble in their respective bearings, sprocket wheels on said shafts, sprocket wheels on the driven shaft and chain belts extended over said sprockets to drive the rolls.

5. In a woodworking machine, a feed table, a cutter head, feed rolls arranged in tandem for the feeding of strip material across said table to the cutter head, a drive shaft for each roll, a bearing for each drive shaft, a driven shaft mounted between and parallel with the drive shafts for the rolls, supporting arms extending from the bearings and pivoted on the driven shaft for upward and downward swinging of the feed rolls relative to the table, a vertical guideway associated with the table, a vertical pressure bar mounted for up-and-down adjustment in the guideway extending above and disposed between the longitudinal axes of said rolls, a lug extending upwardly from each of said bearings and having a horizontal passage extending through the same, each of said arms extending through the passage in one of the lugs with clearance, whereby downward force may be transmitted from the pressure bar to the roll to press the roll into driving contact with a strip being advanced beneath it, and a limited downward movement of the roll relative to the pressure bar without transmission of downward force against the roll by the arm is permitted when the roll is not in contact with an advancing strip, said downward movement of the roll being definitely limited by the engagement of the arm with the lug to that permitting easy pick-up by the roll of the next strip advanced thereto, weighted means for urging the pressure bar downwardly, an adjusting screw on the pressure bar engageable with a part on the table for limiting the downward movement of the pressure bar, and means for driving the feed rolls in unison from said driven shaft.
